ATTORNEY

UNITED STATES PATENT OFFICE.

ORVILLE M. KNOX, OF ONEIDA, NEW YORK.

VEHICLE-HOLDBACK.

SPECIFICATION forming part of Letters Patent No. 769,389, dated September 6, 1904.

Application filed December 18, 1902. Serial No. 135,661. (No model.)

To all whom it may concern:

Be it known that I, ORVILLE M. KNOX, a citizen of the United States, and a resident of Oneida, in the county of Madison, in the State 5 of New York, have invented new and useful Improvements in Vehicle-Holddbacks, of which the following, taken in connection with the accompanying drawings, is a full, clear, and exact description.

10 This invention relates to the class of holddback attachments which comprise a base-plate secured to the thill of the vehicle, a keeper pivoted to said base-plate to receive the holddback-strap of the harness, and means for sus- 15 taining said keeper in position to retain the holddback-strap in its proper operative position and capable of automatically releasing said strap in the operation of unhitching the horse or in case of accidental detachment of 20 the traces of the harness.

The invention consists in the improved construction and novel arrangement of parts of a holddback, as will be hereinafter more fully set forth.

25 In the accompanying drawings, in which each reference-letter indicates the same part in each of the views in which it occurs, Figure 1 is a side view of a holddback embodying my improvements, with the holddback-strap of the 30 harness shown in dotted lines. Fig. 2 is an inverted plan view of the same. Fig. 3 is a transverse section on the line X X in Fig. 2, and Fig. 4 is a detached inverted plan view of the keeper.

35 *a* represents the base-plate of the holddback attachment, which is elongated and perforated at its ends for the reception of screws *b b* or other suitable attaching devices by means of which the plate is fastened to the under side 40 of the thill *T*.

C indicates the keeper to which the holddback-strap *S* of the harness is connected, as shown in dotted lines in Figs. 1 and 2, when the horse is hitched to the vehicle. This 45 keeper is pivoted at one end to a post *d*, which is attached to or projects from the plate *a* at or near one of the side edges thereof, and the rearward swinging of said keeper is limited by a stop *e*, which projects downward from 50 the opposite edge of the base-plate *a* and is

in position to allow the free end of the keeper to lie against the front of the stop when the keeper is in its normal position to retain the holddback-strap thereon. The pivotal end of the keeper *C* is provided with a hollow or socketed hub *c*, through which the post *d* is passed, the inner end of the hub being seated directly upon the base-plate *a* and provided on its edge with a notch or recess *n* and the outer end perforated, through which the post *d* is passed for holding the inner end against the plate. The socket *g* of the hub extends nearly to the outer end or to a point past the axial center of the keeper and is provided at its bottom with a recess *h*, which extends radially therefrom and substantially in line with the axis of the keeper. F represents a spiral spring which forces the keeper to its normal closed position on the stop *e*. This spring is arranged in the socket *g*, formed in the hub of the keeper *C* and surrounds the post *d*. The wall of the socket forms a shield over the spring to protect the same. Two lugs *l* and *m* project from the plate *a*, one on each side of the hub, one of which, *m*, forms a stop for a projection *p* on the hub, and the other end is provided with a groove or recess *l* at its base for the reception of one end of the spring *F*. The projection *p* extends substantially radially from the hub and at right angles to the keeper *C*, and the recess *n* is located diametrically opposite the projection *p* and is only of sufficient length to permit of the free end of the keeper being swung away from the stop *e* to permit of the insertion of the holddback-strap *S*. By 55 constructing the keeper and its hub in this manner the depth of the recess is sufficient to permit the use of a longer and stronger spring than has heretofore been possible, which adds very materially to its life by increasing its 60 size and decreasing its liability to breakage. It also permits of the inner end of the spring being entirely inclosed, and thereby protecting it from the water and other foreign substances that would have access to it if it were 65 seated in an open or exposed slot or recess. It will also permit of the notch *n* in the end of the hub being reduced to the least possible size, thereby giving the hub a larger bearing 70 on the plate *a* and also presenting the small- 75 100

est-sized orifice through which water and other foreign substances can gain access to the interior of the recess or socket *g*, and by seating the projecting end of the spring in the 5 recess *i* only a small portion of the spring between the hub and the stop-lug *l* is really exposed and the tip or free end is completely shielded, which will prevent its catching upon the strap *S* or other object. To prevent the 10 free end of the keeper from being pressed toward the base-plate by the strain upon it in that direction by the strap *S*, the stop *e* is provided with a seat or shoulder *o*, against which said end of the keeper rests when in its 15 normal or operative position. This shoulder is only of sufficient depth or size to afford the necessary support for the keeper, and the face *t* of the portion of the stop between it and the tip is substantially straight or slightly 20 retracted sufficiently to permit of its being cast complete or without requiring other manipulation to form the shoulder. The other faces of the stop are made straight or inclined toward the tip, which also permits of the easy 25 removal of the pattern from the mold. The shoulder is located at a distance from the base-plate equal to the length of the hub projecting from one side of the keeper, so that the keeper will be held parallel with said plate. An 30 other advantage secured by forming the shoulder without any portion of the stop projecting beyond or overhanging it is that in introducing the strap *S* onto the keeper it is only necessary to move the free end of the 35 keeper away from the stop a little more than the thickness of the strap, which will thus permit of the strap being slipped upon the keeper from a position beyond the stop and in alignment with the keeper.

40 I am aware that prior to my present invention a seat has been formed in the stop *e*, but it was made semicircular to receive the form of keeper coöperating therewith; but by constructing the keeper at the pivotal end, as 45 above described, the wall of the seat can be formed straight, as shown in Fig. 1. It is obvious that a semicircular seat cannot be formed on the stop simultaneously with the casting

of the base-plate, inasmuch as it does not permit the pattern to be withdrawn vertically 50 from the mold without destroying the mold. Consequently the said semicircular seat can only be formed by cutting it in the stop after the casting has been removed from the mold, and thus the cost of manufacture is considerably increased. 55

Having thus described my invention, I claim—

A vehicle-holdback comprising a perforated base-plate and a spring-actuated keeper pivotally mounted thereon, one side of the plate being provided with two stops at one edge and one stop at the opposite edge, one of the two stops being provided at its base with a groove and the single stop being provided with a shoulder near its tip, the portion of the stop from the shoulder to the tip being straight and the keeper being provided at its pivotal end with a socketed hub extending from one side a distance equal to the distance that said shoulder is from the base-plate, and said socket extending into the hub to a point beyond the axial center of the keeper and having a recess extending radially therefrom substantially in line with the keeper, the edge of 75 the inner end of the hub being provided with a recess and the opposite end with a projection substantially at right angles to the keeper, said projection and recess in the edge of the hub being substantially diametrically opposite each other, a headed post extending through the outer end of the hub and axially through said socket and engaging with the base-plate at a point between said two stops, and a coil-spring around said post in the 80 socket, the inner end of the spring being seated in said recess in the socket and the outer end projecting through the recess in the edge of the hub and resting in said groove at the base of one of said two stops, substantially as 85 described.

ORVILLE M. KNOX.
